(57) **CLAIM**

The ornamental design for a multi-purpose flagpole bracket,
as shown and described.

DESCRIPTION

FIG. 1 is a perspective view of the multi-purpose flagpole
bracket of this invention.

FIG. 2 is a front elevational view thereof.

FIG. 3 is a right side elevational view thereof.

FIG. 4 is a rear elevational view thereof.

FIG. 5 is a left side elevational view thereof.

FIG. 6 is a top plan view thereof.

FIG. 7 is a bottom plan view thereof; and,

FIG. 8 is a cross-sectional view thereof taken along lines 8—8
of FIG. 1.

The broken lines in the drawings represent unclaimed envi-
ronmental subject matter.
